EJECTING MEANS FOR CAP FORMING MACHINES

Leo M. Harvey, Los Angeles, Calif.

Application October 16, 1940, Serial No. 361,331

13 Claims.

(Cl. 93—60)

This invention relates to cup forming machinery and relates more particularly to an ejecting means for a paper cup forming machine. A general object of this invention is to provide an effective, dependable, automatic cup ejecting means for a paper cup forming machine.

Another object of this invention is to provide an improved cup ejecting means useful on cup forming machines of the general character disclosed in United States Letters Patent 2,215,698, granted to me, September 24, 1940.

Another object of this invention is to provide an ejecting means of the character referred to which automatically withdraws the finished cups from between the dies of the machine immediately upon completion of the cups without injuring or distorting the cups and without delaying or interfering with the operation of the dies.

Another object of this invention is to provide a mechanism of the character referred to which operates to accurately count the completed ejected cups serving to deliver or discharge at regular intervals a given number of stacked nested cups as unitary groups suitable for handling and packaging.

Another object of this invention is to provide a cup ejecting and counting mechanism of the character mentioned embodying novel means for compacting or pressing the finished cups into firm nested relation to form a stable, compact assembly or stack which may be handled and packaged without danger of separation.

A further object of this invention is to provide a cup ejecting and counting means of the character referred to which is dependable and accurate, being synchronized with the other machine elements to operate without manual regulation or attention.

The various objects and features of my invention will be fully understood from the following detailed description of a typical preferred form and application of the invention, throughout which description reference is made to the accompanying drawings, in which:

Fig. 1 is a vertical detailed sectional view of a portion of the paper cup forming machine showing the ejecting means and counting means in side or edge elevation and illustrating the operating means for the ejector in the condition where the ejector is being retracted. Fig. 2 is an enlarged fragmentary vertical detailed sectional view of a portion of the die assembly at the completion of the cup with the ejector in position at the dies. Fig. 3 is a view similar to Fig. 1 showing the bead forming dies separated

and the ejector in engagement with the cup bead. Fig. 4 is a side elevation of the cup forming machine showing the means of the invention arranged thereon with its parts in the idle positions. Fig. 5 is an enlarged horizontal fragmentary sectional view showing the ejector in engagement with the finished cup preparatory to shifting it to the receiver. Fig. 6 is a fragmentary vertical sectional view showing certain of the dies in side elevation and illustrating the cup handling positions of the ejector, and Fig. 7 is an enlarged detailed sectional view of a portion of the counting means.

In the drawings I have shown the mechanism of the invention associated with a cup forming machine of the character described in my issued patent referred to above. It is to be understood that the invention may be applied to machines varying somewhat in construction and operation and may be modified to suit it for use on different machines.

It is believed that the invention will be best understood by first describing, in a more or less general manner, the paper cup forming machine and its mode of operation, it being understood that a full disclosure of the machine is not required as this is to be found in the above referred to issued patent.

The paper cup forming machine comprises a supporting structure or frame 10 housing an electric motor 11, or other suitable power means which drives the various machine elements through a belt and pulley drive 12. A stationary horizontal cross head 13 is supported in the upper portion of the frame 10 and two spaced vertically shiftable cross heads 14 and 15 are arranged in the frame 10 above the stationary cross head 13. Two spaced vertically shiftable cross heads 16 and 17 are guided in the frame 10 below the stationary cross head 13. The shiftable cross heads 14, 15, 16 and 17 carry certain cup shaping die elements and are controlled and operated by cam rods 18, which in turn are controlled by cams (not shown) on driven shafts 43 and 41. The die assembly comprises a die A on the stationary cross head 13 and a die B on the cross head 16 which are cooperable to form flutes in the cup blank. A male cup shaping die C is carried by the cross head 14 and is shiftable through or in the stationary fluting die A. The female cup shaping die D is shiftable in or through a bead forming die F carried by the cross head 17, the die D being operated and controlled by a cam means (not shown). An upper bead forming die E surrounds the die C

and is carried by the shiftable cross head 15. A suitable feed means serves to introduce the blanks between the fluting dies A and B.

The general sequence of operation of the dies referred to above is as follows:

(1) The paper cup blank is fed between the dies A and B;

(2) The die B moves upwardly so that the blank is fluted by the dies A and B;

(3) The die B moves downwardly to free the 10 blank;

(4) The die C moves downwardly to move the fluted blank from between the dies A and B;

(5) The die C continues its downward movement and the die D moves upwardly so that the 15 blank is given the cup shape by the dies C and D;

(6) The die F moves upwardly relative to the die D to iron out the rim portion of the cup X;

(7) The dies E and F move downwardly relative to the dies C and D to roll a rim bead Y on the cup X;

(8) The dies E and F move apart, the die E being restored to its up position on the die C and the die F moving downwardly relative to the die D as shown in Fig. 3;

(9) The dies F and D move downwardly;

(10) The die C moves upwardly to strip or free the cup X;

(11) And the die B moves downwardly to its initial position for the next operation.

The mechanism of the present invention may be said to comprise, generally, an ejector 20 operable to grip the finished cups X and shift them from between the dies, means 27 synchronized with the cup forming machine for operating the ejector 20, and cup assembling and counting means 22 receiving the cups X from the ejector 20.

The ejector 20 is provided to shift the cups X from between the spaced opposed dies C and E and D and F to the cup assembling and counting means 22. The ejector 20 is an elongate lever-like element supported for vertical shifting and for pivoting about a vertical axis. The ejector 20 is arranged at what will be termed the discharge side of the cup forming machine and is carried by a vertical shaft or pin 23. The pin 23 is fixed to the intermediate part of the ejector 20 and is shiftable in a vertical opening 25 in the cross head 16 of the die B. The lower portion of the pin 23 is guided in an opening in a bracket 24 fixed to the cross head 17 of the die F. The vertical pin 23 is offset laterally from the die assembly. The opposite end portions or arms of the lever-like ejector 20, which join adjacent the pin 23, are angularly related as illustrated in Fig. 5 to bring the inner part of the ejector into correct relation to the die means and the means 22 and to correctly locate the outer portion of the ejector for connection with the operating means 21.

The forward end or inner end of the ejector 20 is provided with novel means for engaging about the finished cups X and for gripping their beads Y. A substantially semi-circular cup engaging finger 26 is riveted or otherwise fixed to the inner or active end of the ejector 20. The finger 26 may have flat upper and lower sides and is shaped to have extensive engagement with the upper sides of the cup beads Y. A shiftable finger 27, similar in shape to the finger 26, is spaced below the finger 26 and is provided to engage about the bodies of the cups X and to grip upwardly against the beads Y. The lower ejector finger 27 is mounted so that it may be pivoted or shifted

upwardly against the beads Y to cause the beads to be gripped between the fingers 26 and 27. A channel shaped carrier 28 is arranged under the forward arm of the ejector 20 and has ears 29 intermediate its ends pivotally secured to the ejector by a horizontal pivot pin 30. The finger 27 is fixed to the forward part of the carrier 28 to be supported and shifted by the carrier. The finger 27 is shaped and mounted to be substantially parallel with the finger 26. A yoke 31 is provided on the outer or rear end of the carrier 28 and straddles the pin 23. A coiled spring 32 is arranged on the pin 23 to be under compression between the yoke 31 and the under side of the ejector 20. During certain phases of the operation the spring 32 urges or pivots the carrier 28 to cause the finger 27 to grip upwardly against the under sides of the cup beads Y. A longer and stronger coiled spring 33 is arranged on the pin 23 between the bracket 24 and the under side of the yoke 31.

With the die B in its dwelling position following operation 3 and prior to operation 9 the cross heads 16 and 17 are in the relation illustrated in Fig. 4 where the springs 32 and 33 are both under compression to hold the ejector 20 up against the under side of the cross head 16. Under this condition the stronger spring 33 overcomes the weaker spring 32 and holds the carrier 28 in the position where the finger 27 is in its lower or released position. Upon downward movement of the dies D and F at operation 9 the large spring 33 is relieved of compression and the small spring 32 pivots the carrier 28 to bring the finger 27 into gripping engagement with the cup bead Y.

The means 21 for operating the ejector 20 is timed in synchronism with the other elements of the machine and serves to move the active end of the ejector 20 between its idle position or plane L to the position M where it receives the cup X, then to the cup releasing positions N and O at the means 22 and then back to its original idle positions (see Fig. 6). The means 21 includes a bell crank pivoted on a horizontal shaft 34 in the case 10 and provided with a long upstanding arm 35 and a shorter generally horizontal arm 36. A link 37 is secured to the upper end of the arm 35 by a universal joint 38 and extends toward the rear end of the ejector 20. A swivel joint or universal joint 39 connects the link 37 with the ejector 20. The joints 38 are operative to transmit movement to the link 37 and ejector 20, while permitting vertical movement of the ejector independently of the link.

Power driven cam means is provided to impart a special or timed movement to the bell crank arms 35 and 36 to operate the ejector 20 through its shuttle-like motions. A freely rotatable roller 40 is mounted on the end of the bell crank arm 36 and is engaged by a pair of cams 41 and 42. The cams 41 and 42 are keyed or fixed to the power driven cam shafts 43 of the cup forming machine. The cams 41 and 42 cooperate with the roller 40 to control and operate the bell crank 35-36. The cams 41 and 42 have rather extensive cylindrical concentric surfaces 41^a and 42^a, respectively, which cooperate with the roller 40 to hold the ejector 20 in its idle position. Pitched and then cylindrical faces 41^b and 42^b are formed on the cams to produce swinging of the ejector 20 toward the cup bead Y and dwelling of the fingers 26 and 27 above and below the bead. Surfaces 41^c and 42^c continue from the surfaces 41^b and 42^b and co-operate with the roller 40 to produce swinging of the ejector 20 to a po-

sition where the cup X is above the means 22. Substantially cylindrical concentric dwell surfaces 41^d and 42^d continue from the surfaces 41^c and 42^c to hold the ejector in line with the means 22 as the cup is moved into the means 22, as will be later described, and restoring surfaces 41^e and 42^e extend from the surfaces 41^d and 42^d to the surfaces 41^a and 42^a to return the ejector to its idle position. The sequence of action of the cams 41 and 42 with relation to the die actions, etc., will be later described.

The cup assembling and counting means 22 receives the finished cups X from the ejector 28, compacts the cups in closely nested relation and discharges the nested cups when they have been assembled in groups containing a specified or given number of cups. The means 22 includes an upright tubular cup receiver 44. The receiver 44 is supported at the outer side of a plate 45 arranged at what I have termed the discharge side of the machine. Studs or bolts 46 provided with spacers mount the plate 45 on the frame 10 of the machine in spaced relation to the adjacent face of the machine. Brackets 47 secure the receiver 44 to the plate 45 in spaced relation to the plate. The upper and lower ends of the receiver 44 are open and the upper end of the receiver may be flared to better receive the cups X. A vertical slot 48 may be provided in the outer side of the receiver 44 to make the cups X visible and accessible.

Means is provided for controlling the delivery or discharge of the cups from the receiver 44. Cup supporting or retaining fingers 49 are spaced a short distance below the lower end of the receiver 44 to be engageable by the bottom of the lowermost cup in the cup stack or assembly being assembled in the receiver. The fingers 49 extend inwardly toward one another and their inner ends or edges may abut when in the normal active positions. The fingers 49 are fixed to the lower ends of depending arms 50 which extend upwardly at opposite sides of the receiver 44. Horizontal pivot pins 51 are provided on the plate 45 to pivotally support the arms 50 from their upper ends. The finger supporting arms 50 are linked together for simultaneous movement. Transverse bars 52 are fixed to the upper parts of the arms 50 and pass inwardly behind the receiver 44 to have overlapping end portions. A pin 53 on one of the bars 52 is shiftably received in a slot 54 in the other bar 52 to link or connect the bars for simultaneous pivotal movement. Spring means is provided for yieldingly holding the arms 50 in the positions where the fingers 49 prevent the discharge of the cups X from the receiver 44. In the case illustrated, a tension spring 55 is anchored to the plate 45 and is connected with a projection or lug 56^a on one of the arms 50 to yieldingly urge the arms 50 to their active positions illustrated in Figs. 1 and 4.

Ratchet counting means is provided to shift the arms 50 to positions where the fingers 49 have been retracted when a given number of cups X have been deposited in the receiver 44. This counting means includes a ratchet wheel 56 rotatably supported behind the receiver 44 by a horizontal shaft 57 on the plate 45. An arm 58 is freely swingable on the shaft 57 and extends outwardly beyond the periphery of the wheel 56. A pivoted pawl 59 is mounted on the arm 58 to cooperate with ratchet teeth 60 on the periphery of the wheel 56. Upon upward swinging of the arm 58 the pawl 59 engaged with a tooth 60 op-

erates to advance or turn the wheel 56. The pawl arm 58 is controlled or operated by the cross head 17 of the die F. An upstanding link 61 is pivotally connected with the outer end of the arm 58 and is operatively coupled with the cross head 17. The stroke of the cross head 17 is greater than that required for advancement of the wheel 56 and a slack connection is provided between the link 61 and the cross head 17. This connection may comprise a longitudinal slot 62 in the link 61 receiving a pin 63 in the cross head 17. A spring 64 may be connected between the link 61 and the pawl 59 to urge the pawl to its wheel-engaging position. A pawl 65 may be pivoted on one of the pins 51 to engage the ratchet teeth 60 and prevent retrograde movement of the wheel. A spring 66 holds the pawl 65 in engagement with the wheel 56. Upon each upward movement of the die F during operation 6 the pawl 59 advances the wheel 56 the width of one tooth 60. The number of ratchet teeth 60 and the capacity of the receiver 44 are related so that the wheel 56 completes one revolution in the time required to feed a specified number of cups X to the receiver 44, said number of cups substantially filling or occupying the receiver.

Means is provided for releasing the control fingers 49 upon each complete revolution of the counting wheel 56. One of the bars 52 is provided with a projecting lug 67 and a pin 68 projects from the side of the wheel 56 to cooperate with the lug. Once during each revolution of the wheel 56 the pin 68 engages the lug 67 to pivot or swing the bars 52 and thus move the fingers 49 to retracted positions clear of the bottom of receiver 44. This allows the assembly or stack of cups X in the receiver 44 to fall or discharge from the receiver. Means may be provided for receiving the assemblies or stacks of cups thus discharged from the receiver 44. In the drawings I have illustrated an elongate container or receiver 69 removably mounted below the receiver 44 to catch the stacks or assemblies of cups which are freed when the fingers 49 are retracted. The receiver 69 may have projecting ears 70 adjacent its upper end removably engaged in hangers 71 projecting from the plate 45.

The invention includes means for compacting or closely nesting the cups X delivered to the receiver 44. This means includes a vertical rod 72 shiftably guided by brackets 73 and 74 on the cross head 14 and 16, respectively. A downwardly facing pusher or plunger 75 is fixed on the lower end of the rod 72. The plunger 75 is vertically aligned with the receiver 44 and is shaped and proportioned to press downwardly against the upper faces of the cup beads Y when the rod 72 is moved downwardly. The rod 72 and plunger 75 are operated by the cross head 11 of the die C. A washer 76 is engaged against a nut on the upper end of the rod 72 and a coiled spring 77 surrounds the rod between the bracket 73 and the washer 76. The spring 77 normally yieldingly holds the rod 72 elevated where the plunger 75 is above the receiver 44 and out of the path of movement of the ejector 28. A collar 78 is fixed on the rod 72 below the bracket 73 to be engaged by the bracket for the transmission of downward movement to the rod. The movement or stroke of the cross head 14 is greater than that required for the plunger 75 and the collar 78 is spaced below the bracket 73 when the cross head 14 is in the idle raised po-

sition illustrated in the drawings. When the die C moves downwardly during operation 4 the bracket 73 engages the collar 78 to shift the plunger 75 downwardly. The plunger 75 does not act on the ejected cups X until there has been a sufficient number of cups delivered to the receiver 44 to cause the stack of cups to protrude from the top of the receiver. The plunger 75 is engageable with the uppermost protruding cup X and its downward movement subjects the nest or stack of cups X to a slight compression sufficient to closely nest the entire series or group of cups delivered to the receiver 44 during one complete revolution of the wheel 56.

With the cup forming machine in operation the dies A to F, inclusive, perform the cup shaping and bead forming operations outlined above and the cams 41 and 42 are continuously operated to control the ejector 20. The operation of the cup ejecting and counting mechanism of the invention considered in conjunction with the general series of die operations outlined above is as follows: When the die B is moved up against the die A at operation 2 the cam faces 41^a and 42^a are engaging the roller 40 so that the ejector 20 is held in its retracted position and the upward movement of the die B is accompanied by upward movement of the ejector 20 under the action of the expanding spring 33. When the die B moves down a short distance to free the cup blank at operation 3 the ejector 20 is shifted downwardly a short distance and is brought to the horizontal plane which will be occupied by the bead Y of the completed cup X. During these operations 2 and 3 sufficient compression is maintained in the spring 33 to hold the gripping ejector finger 27 in the down or released position and the ejector 20 remains in its retracted position, the dwelling surfaces 41^a and 42^a of the cams remaining in cooperation with the roller 40. During operation 4 when the die C is moved downwardly to draw the cup blank from between the dies A and B the plunger 75 is moved downwardly as above described, and may engage against the previously ejected cup X in the event the cup is protruding from the receiver 44. When the die F moves upwardly to iron the rim portion of the cup X at operation 6 the pawl 59 is operated as above described to advance the wheel 56. In the event that the previously completed cup X constitutes the last cup of the counted assembly or stack in the receiver 44 the advancement of the wheel 56 brings the pin 68 against the lug 67 to release the fingers 49 so that the entire group or stack of previously completed cups X is discharged from the receiver. During die operation 7 the ejector 20 remains in its retracted position in the plane to be occupied by the cup bead Y. When the dies E and F separate to positions such as indicated in Fig. 6 the cam faces 41^b and 42^b act on the roller 40 to shift the ejector 20 from the retracted position above mentioned to the position M of Figs. 1 and 6 where the fingers 26 and 27 are ready to grip the bead Y. During the die operation 9 when the dies F and D move downwardly the compression on the spring 33 is relieved and the gripping ejector finger 27 is actuated by the spring 32. This brings the finger 26 into engagement with the under side of the bead Y and the bead is clamped between the fingers 26 and 27. Fig. 3 of the drawings illustrates the positions of the dies at this time and shows the fingers 26 and 27 gripping the bead Y. The engagement of the ejector fingers 26

and 27 with the bead Y holds the cup X against vertical movement so that the cup is stripped from the die C when the latter moves upwardly at operation 10. Following this operation the cam surfaces 41^c and 42^c act on the roller 40 to swing the ejector to the position N of Fig. 6 thus moving the cup X into vertical alignment with the receiver 44. Downward movement of die B during operation 11 produces corresponding downward movement of the ejector 20 moving the ejector to position O in Fig. 6 where the cup X is entered in the receiver 44. The downward movement of die B to its initial position also results in compression of the spring 33 so that the carrier 28 is pivoted and the finger 27 is retracted to free the cup bead Y. During operation 11 the cam surfaces 41^d and 42^d are in cooperation with the roller 40 to hold the ejector 20 in its extended position and immediately following operation 11 the surfaces 41^e and 42^e act on the roller 40 to swing the ejector 20 free of the cup X and back to the position L of Fig. 6. The cam surfaces 41^f and 42^f retain the ejector 20 in position L or in this vertical plane until the ejector is again swung inwardly at operation 8 of the next cycle or die actions.

The cup ejecting means and cup assembling and counting means of the invention operate in synchronism with the cup forming dies of the machine and do not in any way interfere with or retard the cup forming actions. The cups are assembled in compact stacks or assemblies which are easily handled and packaged when discharged from the receiver 44. The mechanism is entirely automatic and requires no manual attention.

Having described only a typical preferred form and application of my invention, I do not wish to be limited to the specific details herein set forth, but wish to reserve to myself any variations or modifications that may appear to those skilled in the art or fall within the scope of the following claims.

Having described my invention, I claim:

1. In a cup forming machine having a series of coacting dies for shaping the cups, the combination of, an ejector for removing the cups from the dies, means for operating the ejector in synchronism with the dies to receive the finished cups, a receiver for receiving the cups from the ejector, and means for compacting the cups in the receiver.

2. In a cup forming machine having die means for shaping the cups, the combination of, a generally upright receiver for the cups, ejecting means for shifting the finished cups from the die means to the receiver, releasable means for preventing the discharge of the cups from the lower end of the receiver, and means for releasing the releasable means when a given number of cups has been delivered to the receiver.

3. In a cup forming machine having die means for shaping the cups, the combination of, a stationary receiver for the cups, ejecting means for shifting the finished cups from the die means to the receiving end of the receiver, releasable means for preventing the discharge of the cups from the discharge end of the receiver, means for compacting the cups in nested series in the receiver, and means for releasing the releasable means when a given number of cups has been delivered to the receiver.

4. In a cup forming machine having die means for shaping the cups, the combination of, a stationary generally upright receiver for temporarily holding the cups, a shiftable member nor-

mally preventing the discharge of the cups from the lower end of the receiver, and ratchet counting means operatively associated with the die means for shifting said member to permit the discharge of the cups from the receiver when a predetermined number of cups has been delivered to the receiver.

5. Ejector means for a paper cup machine having dies for forming paper cups with rim beads comprising an ejector for shifting the completed cups from between the dies, means on the ejector for gripping the upper and lower sides of the rim beads, means for operating the ejector, and means for operating the gripping means.

6. Ejector means for a paper cup machine having dies for forming paper cups with rim beads comprising an ejector movable from a retracted position to a position at the cup in the die means, then to a discharging position and then back to its retracted position, the ejector including means for gripping the upper and lower sides of the rim beads, means operating in timed relation to the die operations for shifting the ejector through the named series of positions, and means for actuating the gripping means when the ejector is at the cup and for releasing the gripping means when the ejector is in the discharging position.

7. Ejector means for a paper cup machine having dies for forming paper cups with rim beads comprising an ejector movable from a retracted position to a position at the cup in the die means, then to a discharging position and then back to its retracted position, the ejector including means for gripping the rim beads of the cups, means operating in timed relation to the die operations for shifting the ejector through the named series of positions, and means for actuating the gripping means when the ejector is at the cup and releasing the gripping means when the ejector is in the discharging position, the last named means comprising a spring for actuating the gripping means controlled by movements of the dies.

8. An ejecting and assembling mechanism for a paper cup machine having relatively movable cup forming dies arranged on a common axis comprising a generally upright stationary receiver at one side of said axis, an ejector for receiving the completed cups and for shifting the cups to the upper end of the receiver, releasable control means for governing the discharge of the cups from the lower end of the receiver, and counting means actuated by relative movement of certain of the dies for releasing the control means when a given number of cups has been delivered to the receiver.

9. An ejecting and assembling mechanism for a paper cup machine having relatively movable cup forming dies arranged on a common axis comprising a receiver at one side of said axis, an ejector for receiving the completed cups and for shifting the cups to the receiver, releasable control means for governing the discharge of the cups from the receiver, means actuated by movement of a die for compacting the cups in the re-

ceiver, counting means actuated by relative movement of certain of the dies for releasing the control means when a given number of cups has been delivered to the receiver.

10. An ejecting and assembling mechanism for a paper cup machine having relatively movable cup forming dies arranged on a common axis comprising a stationary generally upright receiver at one side of said axis, an ejector for receiving the completed cups and for shifting the cups to the upper end of the receiver, cam means operating in synchronism with the dies for actuating the ejector, releasable control means for governing the discharge of the cups from the lower end of the receiver, counting means actuated by relative movement of certain of the dies for releasing the control means when a given number of cups has been delivered to the receiver.

11. Cup ejecting and assembling means for a paper cup forming machine having a series of relatively movable coacting cup shaping dies, said means comprising a stationary tubular receiver having a receiving end and a discharge end, ejecting means for conveying the cups from the dies to the receiving end of the receiver, a movable member for preventing the discharge of the cups from the discharge end of the receiver, lever means for moving said member, counting means advanced a given distance with each cycle of operation of the dies, and means on the counting means for operating the lever means once during a given number of die operations.

12. Cup ejecting and assembling means for a paper cup forming machine having a series of relatively movable coacting cup shaping dies, said means comprising a stationary tubular receiver having a receiving end and a discharge end, ejecting means for conveying the cups from the dies to the receiving end of the receiver, a movable member for preventing the discharge of the cups from the discharge end of the receiver, lever means for moving said member, a rotatable ratchet wheel, pawl means for advancing the wheel with each cycle of die operations, and a part on the wheel for operating the lever means once during each revolution of the wheel.

13. Cup ejecting and assembling means for a paper cup forming machine having a series of relatively movable coacting cup shaping dies, said means comprising a generally upright stationary tubular receiver whose upper end forms the cup receiving end and whose lower end forms the discharge end, ejecting means for conveying the cups from the dies to the receiving end of the receiver, a movable member for preventing the discharge of the cups from the discharge end of the receiver, a plunger movable with one of the dies for pressing against the cups at the receiving end of the receiver to compress the cups in the receiver, lever means for moving said member, counting means advanced a given distance with each cycle of operation of the dies, and means on the counting means for operating the lever means once during a given number of die operations.

LEO M. HARVEY.
